(57) **CLAIM**

The ornamental design for a waste collector, as shown and described.

DESCRIPTION

FIG. 1 is a perspective view of the waste collector of the present invention.

FIG. 2 is front view of the waste collector.

FIG. 3 is a back view of the waste collector.

FIG. 4 is a side view of the waste collector.

FIG. 5 is a side view of the waste collector, showing the opposite side from FIG. 4.

FIG. 6 is a top view of the waste collector; and,

FIG. 7 is a bottom view of the waste collector.

The broken lines illustrate portions of the waste collector that form no part of the claimed design.
